DESICCATING APPARATUS

Edouard Le B. Benoit, Brooklyn, N. Y.

Application June 10, 1939, Serial No. 278,431

6 Claims. (Cl. 34—57)

The present invention relates to treatment of material with a gaseous medium, and has special reference to apparatus for desiccating freshly cut grass, alfalfa, and other fodder.

One of the objects of the invention is to provide an apparatus that is particularly adapted for use in carrying out my improved process, and which is of simple and compact construction, capable of being easily controlled to meet different conditions, and is highly efficient in operation.

The several features of the invention, whereby the above-mentioned and other objects may be attained, will be readily understood from the following description and accompanying drawings, in which:

Figure 1 is a vertical sectional view, partly in elevation, of my improved apparatus in its preferred form;

Fig. 2 is a plan view of the apparatus;

Fig. 3 is a sectional plan view taken substantially on the line 3—3 of Fig. 1; and

Fig. 4 is a sectional view taken on the line 4—4 of Fig. 1.

The apparatus illustrated in the drawings is provided with a treating chamber 2, a magazine 4 for receiving the material to be treated, and a receptacle or collector 6 for receiving the material after it has been treated. These parts may be made of sheet metal and if desired may be suitably heat-insulated.

The lower end of the chamber 2 is provided with a cylindrical wall 8 and a bottom wall 10. A cylindrical baffle 12 is secured on the bottom wall concentrically with the wall 8 so as to provide an annular space about the baffle. Leading tangentially into this annular space is a nozzle 14 on the end of a pipe 16. The gaseous treating medium may be supplied to the apparatus through this pipe and nozzle.

From the upper edge of the cylindrical wall 8, the treating chamber flares upwardly and outwardly forming a conical lower wall portion 18. The upper portion 20 of the treating chamber may be cylindrical and its upper end closed by a top wall 21.

Extending downwardly through a central opening in the top wall 21 is an outlet pipe 22 having its lower end open and spaced a distance below said top wall 21. This pipe leads into the under side of a cylindrical chamber 24 which, through a pipe 26, is in communication with the suction end of a fan 28. A pipe 30 leads from the outlet opening of the fan, and communication may be established between this pipe and gas inlet

pipe 16 through a branch pipe 32 which is controlled by a damper 34.

The magazine 4 is adapted to discharge into the treating chamber 2 through an opening 36 in the side of the upper portion of the treating chamber. This opening is adapted to be opened and closed by a quadrant damper 38 in the lower end of the magazine 4.

The magazine 4 extends a distance above the treating chamber and its upper end is adapted to be opened and closed by a quadrant damper 40. A pipe 42 leads from the upper end of the treating chamber into the upper end of the magazine 4 and is provided with a damper 44.

The collector 6 is in communication with the treating chamber through an opening 46 which is diametrically opposite the opening 36 leading from the magazine 4. This opening 46 is adapted to be opened and closed by means of a door or damper 48 mounted in the collector 6. The collector extends downwardly and outwardly from the opening 46 and its lower end is provided with a discharge opening which is adapted to be opened and closed by means of a hinged door or damper 50.

The upper end of the collector 6 is in communication with the suction pipe 26 through a pipe 52 having a damper 54.

One or more nozzles 56 may lead tangentially into the upper cylindrical portion 20 of the treating chamber 2, the nozzle being in communication with the branch pipe 32 through a pipe 58.

The gaseous treating medium when grass or similar material is being treated, may be air that is heated to the desired temperature in any suitable manner as by a coal or oil furnace, or it may be the products of combustion of such a furnace. The treating medium is drawn through the inlet pipe 16 by a suction set up in the apparatus by the fan 28. The tangential nozzle 14 at the end of the pipe 16 directs the medium through the annular space between the cylindrical wall 8 and the cylindrical baffle 12 and around the latter, and it passes in a rising, whirling and expanding spiral up through the treating chamber 2 and out through the outlet pipe 22.

The freshly cut grass or other material to be treated, may be dropped into the upper end of the magazine 4 by means of a conveyor (not shown) or other suitable means. During the filling of the magazine, the damper 38 closes the opening 36 at the bottom of the magazine and the damper 40 is opened. When a full charge has been dropped into the magazine, the damper 40 is closed thus sealing the magazine. Thereafter the material may be fed into the top of

the magazine where it collects in the quadrant shaped damper 40. Upon again opening the damper 40 the material thus collected may then drop into the magazine and the conveyor may again fill the magazine, thus repeating the load cycle.

When a full charge has thus been deposited in the magazine and the damper 40 closed, the damper 38 may be opened whereupon the material drops by gravity through the opening 36 and into the treating chamber 2. To insure that the pressure in the magazine 4 and in the treating chamber 2 are equal so that the material will freely drop by gravity, the damper 44 in the equalizing pipe 42 is opened.

As the material drops into the treating chamber it immediately thoroughly mixes with and is held in suspension by the gaseous treating agent. When the full charge of material has been dropped into the treating chamber 2, the dampers 38 and 44 are closed and damper 40 opened, the magazine being then ready to receive the next supply of material. After entering the treating chamber 2, the material is whirled in and by the gaseous treating medium, until the treating or curing process has been completed as predetermined by the operator. This time element will vary with the kind of material being treated and the temperature of the treating medium, the temperature being controllable by the operator.

Thus the upwardly whirling current of the gaseous medium thoroughly mixes with and carries suspended in its path the material which is being treated. Upon reaching approximately the point of intersection of the conical lower wall and upper cylindrical wall of the treating chamber, the velocity of the treating medium has been lowered due to the expansion of the conical wall 18 to the extent that it may no longer effectively carry the material in suspension. Consequently, the material tends to drop through the treating medium to a point of higher velocity of the treating medium where it is again carried upwardly in the spiral path of the medium. This results in all of the particles or blades of grass, or other material, being uniformly subjected to the treatment of the gaseous medium and insures uniform drying of the material.

To accelerate the velocity of the gaseous medium within the treating chamber, additional gaseous medium may also be directed tangentially into the upper portion of the treating chamber through a nozzle 56, or a multiplicity of such nozzles may be employed.

Owing to centrifugal force, the material is directed away from the lower end of the pipe 22, while the gas is free to pass upwardly through the pipe as indicated by the arrows.

When the material has been thus treated to the desired degree, the damper 48 is opened so as to cause the material to pass by centrifugal force and by the velocity of the gas through the opening 46 and drop by gravity into the collecting chamber 6. Just prior to the opening of the damper 48, the damper 54 of the equalizer pipe 52 may be opened so as to permit the gaseous medium to be drawn into the collector 6 with the material so as to expedite and insure the passage of all of the material into the collector.

After a time limit sufficient to allow all of the material to enter into the collector 6, the dampers 48 and 54 are closed and the damper 50 is opened permitting the material in the collector to fall by gravity therefrom into a truck or wagon body, or on to a conveyor to be taken to a de-

sired point, thus completing the passage of the material through the apparatus.

Upon closing the damper 48, the damper 40 is also closed, and the damper 38 is opened permitting the next charge of material to be dropped into the treating chamber for treatment.

The fan 28 blows the gas through pipe 30 where all or part thereof may be diverted by the damper 34 through the branch pipe 32 where it is returned to the treating chamber. If part of the gas is allowed to escape and part returned to the treating chamber, the loss may be made up by the heated air or products of combustion from the furnace.

15 The several dampers of the apparatus may be operated automatically in proper timed relation as above described by suitable mechanism (not shown) connected therewith.

It will be apparent from the foregoing that the 20 treating medium as it passes through the treating chamber comes in contact with and thoroughly mixes with the material and carries said material in suspension for such time as may be required to complete the treatment.

25 The treating medium is introduced into the treating chamber in a steady flow which rises in a spiral movement of varying velocity and carries the material in suspension therewith by its velocity and by centrifugal force applied against 30 the gravity of the material. As the velocity of the treating medium decreases, the material drops by gravity to a point of higher velocity. The treating medium continues on its path leaving the treating chamber to be returned in whole or in part to the initial point of introduction.

35 This action of the material in the treating medium allows contact and thorough mixing of the medium with the material, thus making the process highly efficient and insuring uniform results. The material remains in contact with the treating medium until such time as the treatment is completed.

40 In the case of grass or similar material and heated air as the treating medium, the heat is transferred from the air to the grass and moisture in the grass is evaporated, and at the same time the air becomes a carrier for the water vapor liberated.

45 I have found that in the drying of grass especially, it is advantageous to use products of combustion as a treating medium provided the combustion in the furnace employed is substantially complete, because carbon dioxide is present and the oxygen content is low. As the products 50 of combustion are recirculated and reheated the gas becomes a mixture of products of combustion and steam. This combination produces an excellent drying agent for material such as grass. It is essential that the temperatures of the mixture always exceed 212° F. At temperatures exceeding 212° F. and normal atmospheric pressure, the steam in the mixture is in a superheated state and therefore has the properties of absorbing large quantities of water vapor without 55 danger of reaching the dew point.

60 I have found that gas temperatures for drying grass may be as high as 1350° F. without injury to the grass provided there is sufficient moisture being vaporized to cool the blades of grass. Temperatures above 600° are advantageous in destroying virus fungi and bacteria. I have also found that as the grass approaches the dry state 65 it is essential that the temperature of the grass does not exceed 275° F. and preferably 250° F. so as not to injure or burn the product.

In view of the foregoing, therefore, the temperature of the gas should be reduced from the high temperature, 1350° F., to a final temperature at the end of the drying cycle of 250° F. This is easily accomplished because the grass is dried in a batch and the quantity of gas in the whole system is relatively small. I have found in some cases that the source of heat may be completely shut off at some point in the drying cycle, the heated walls of the dryer being a sufficient source of heat to prevent the temperature from dropping below 212° F. at which point condensation would occur.

I have found that the aforesaid method of suspending the grass in the current of gas and by recirculating part of the gas together with the aforesaid varying temperatures for the drying cycle produces grass in a dried state which retains its color, high protein value, is free from spores and bacteria, and is in every respect desirable for cattle feed. The high temperature used and the benefits of recirculation combine to produce dried grass at a high fuel efficiency.

My improved apparatus requires low initial expense for construction and setting it up, and low maintenance costs and high fuel efficiencies.

As will be evident to those skilled in the art my invention permits various modifications without departing from the spirit thereof or the scope of the appended claims.

What I claim is:

1. In an apparatus for treating material of the class described, the combination of a treating chamber vertically arranged, having the lower portion thereof flaring upwardly and outwardly in conical form and having the upper portion thereof substantially cylindrical, means for directing a current of a gaseous medium into the lower end of the treating chamber, means for causing the current to take an expanding spiral path as it travels upwardly through the chamber, means for withdrawing the gaseous medium from the vertical central portion of the chamber at a point spaced a distance below the upper end of the chamber, a magazine having a port in its lower end opening into the upper part of said chamber, controllable means for opening and closing said port, said magazine having an opening in the upper part thereof through which a measured quantity of said material may be deposited in the magazine when said port is closed, controllable means for closing said opening when the material has been deposited in the magazine, a receptacle having a port in the upper portion thereof leading from the upper part of said treating chamber, and controllable means for opening and closing the second-mentioned port.

2. In an apparatus for treating material of the class described, the combination of a treating chamber vertically arranged, means for directing a gaseous medium into the lower end of the chamber and withdrawing it from the upper end of the chamber, means for redirecting a part of the gaseous medium thus withdrawn from the chamber in a generally tangential di-

rection into the upper part of said treating chamber, means for delivering material to the treating chamber, and means for effecting the discharge of material from said chamber.

5. In an apparatus for treating material of the class described, the combination of a treating chamber vertically arranged, means for directing a gaseous medium upwardly through the chamber in a generally spiral path, a magazine for 10 receiving the material to be treated having a port leading into the upper part of said treating chamber, means for opening and closing said port, a collector for receiving the material from the treating chamber having a port leading from the upper part of said chamber, and means for opening and closing said port in the collector.

15 4. In an apparatus for treating material of the class described, the combination of a treating chamber vertically arranged, means for directing a current of a gaseous medium into the lower part of the chamber and for causing it to take an expanding spiral path as it travels upwardly through the chamber, means for withdrawing the gaseous medium from the vertical central portion of the chamber at a point spaced a distance below the upper end of the chamber, controllable means for admitting a measured quantity of the material into the upper part of the chamber at one side of the center thereof, and controllable means for effecting the discharge of the material from the other side of the upper part of the chamber after the entire quantity of material has been subjected to the treatment of said gaseous medium.

20 30 35 5. In an apparatus for treating material of the class described, the combination of a treating chamber vertically arranged, means for admitting a gaseous medium into the lower part of the chamber, means for withdrawing the gaseous medium from the upper end of the chamber, a magazine at one side of the chamber having a port in the lower end thereof leading into the upper part of said chamber, controllable means for opening and closing said port, said magazine having an opening in the upper end thereof, controllable means for opening and closing said opening, a conduit leading from the upper end of the magazine to the upper part of said treating chamber, and means for opening and closing said conduit, and means for discharging the material from said treating chamber.

40 45 50 55 60 65 6. In an apparatus for treating material of the class described, the combination of a treating chamber, means for directing a gaseous medium into the lower part of the chamber, means for withdrawing the gaseous medium from the upper part of the chamber, a collector at one side of said chamber having a port leading from the upper part thereof to the upper part of said chamber, controllable means for opening and closing said port, a conduit leading from the upper portion of the collector into said medium withdrawing means, means for opening and closing said conduit, and means for charging material into the treating chamber.

EDOUARD LE B. BENOIT.
